DISPLAY RACK FOR NUTS AND BOLTS OR THE LIKE

George G. Charlton, Rte. 3, Box 67,
Ellensburg, Wash. 98926

Filed Aug. 16, 1971, Ser. No. 172,363

Term of patent 14 years

Int. Cl. D6—06

U.S. Cl. D6—125

FIG. 1

FIG. 2

FIG. 1 is a top left front perspective view of a display rack for nuts and bolts or the like embodying my new design.

FIG. 2 is a bottom right rear perspective view.

I claim:

The ornamental design for a display rack for nuts and bolts or the like, substantially as shown.
